COMBINED CONTAINER CLOSURE AND APPLICATOR

Benjamin S. Thorp, Frankford, Pa., assignor to
Whitall Tatum Company, New York, N. Y., a
corporation of New Jersey

Application May 4, 1935, Serial No. 19,792

4 Claims. (Cl. 91—67.2)

This invention relates to combined container closure and applicator devices. The invention is more particularly applicable to containers such as bottles of the type for containing liquids such as mercurochrome, iodine, collodion and the like, which are to be dispensed by means of an applicator such as a brush or glass rod projecting downwardly into the liquid.

In such devices it is desirable that the closure 10 perform the function of closing the container to a degree to prevent evaporation of, or exposure to the air, of the contents, and that it also provide supporting means for the applicator which extends into the container and is immersed in the liquid.

It is customary to employ for this purpose a closure in the form of a cap made of suitable synthetic plastic products, such as bakelite, hard rubber, etc., the cap being provided with a depending skirt internally threaded or grooved for attachment to the container. In order to prevent seepage of the liquid it is highly desirable that the cap be provided with a gasket for interposition between the cap and the rim of the container. Also, the cap must be provided with some appropriate means for affixing the applicator thereto.

Both of these requirements have introduced serious difficulties in the provision of a simple, economical and commercially feasible combined container closure and applicator device. The gasket, owing to its necessarily flexible composition and the cementing action of various of the contained fluids, tends in use to adhere to the neck 35 of the container and to pull away from the cap. Attempts to avoid this by cementing the gasket to the cap have not proved very successful because no satisfactory adhesive has as yet been devised which will provide a permanent bond 40 between the gasket and the cap, particularly if the latter is made of such a substance as bakelite. Moreover, many of the liquids, for which combined containers and applicators of the general type are primarily intended, include as an essential ingredient such a universal solvent as 45 ether or chloroform, which will destroy the bond provided by most cements.

Similarly, the applicator stem being usually of glass or feather quill cannot successfully be cemented to a cap of the composition aforesaid; and if attached by known methods to the gasket in accordance with known practices, will increase the tendency of the gasket to separate from the cap.

According to my invention, I overcome these defects in a simple and highly efficacious manner by providing the cap with an internally depending central stud or peg integral with the cap. As a means of securing the applicator to the cap and also serving as a gasket between the

cap and container, I further provide a flexible member, of rubber or the like, which is of substantially cylindrical contour but terminating at one end in a radially projecting flange. Each end of this member contains a central bore extending axially inward to an intermediate depth leaving thereby an impervious transverse wall of the material between the two bores.

The bore adjacent the flanged end of the member is adapted to slip over while tightly gripping the cap peg until the flange is flush with the inner surface at the top of the cap. The outer diameter of the flange is such as likewise to engage the inner diameter of the cap in a snug fit. The flange thus serves as a gasket between the cap and the container, which, owing to the gripping action aforesaid, will be retained in integral assembly with the cap without the necessity for cementing the two, although an adhesive may be employed if desired.

The opposite bore of the flexible member is such as to receive the upper end of the applicator stem in a snug fit. If, therefore, an attempt is made to pull the stem away from the cap the flexible member in stretching will grip both the stem and the cap stud even more tightly and thereby prevent separation of the assembly. Moreover, the transverse wall interposed between the two bores will preclude seepage of the contained fluid between the flexible flange and the cap such as would dissolve an adhesive if employed or otherwise tend to separate the two.

In the drawing:
Fig. 1 is a cross sectional view in elevation showing certain details of the device;

Fig. 2 is a view in elevation with certain parts in section and illustrates the device in its intended position when used in closing a bottle, and

Fig. 3 is a cross sectional view taken at 1—1 of Fig. 1.

Referring to the drawing: The numeral 1 designates a cap which is molded of a synthetic plastic material or the like or other suitable material, such as hard rubber. The cap is provided with a top wall 2 and a depending skirt 3 45, internally threaded as at 4 to provide suitable means for engaging cooperating means such as threads 5 on the exterior of a container such as a bottle 6. A downwardly extending peg 7 is formed integrally with the top wall 2 and is centrally positioned within the skirt 3.

A connecting member 8, made of suitably elastic material, such as of resilient rubber, has an upper outwardly extending flange 9 and a centrally disposed downwardly extending stud 10; the flange 9 being of such size and so positioned that when its upper face lies in contact with the inner face of the top wall 2, its peripheral edge is in contact with the inside wall of the skirt 3, and the stud 10 being of a lesser diameter than 60.

the internal diameter of the neck of the bottle 6 (Fig. 2). The member 8 is provided with axially disposed bores or recesses 11 and 12 which extend inwardly from respective upper and lower faces 5 of said member; the bores being discontinuous axially and being separated by a wall portion 13 which is impervious to liquids such as heretofore mentioned.

The bore 11 is of such diameter as to provide 10 a socket portion into which the peg 7 is positioned and is thereby resiliently gripped so as to secure the connecting member 8 in the position illustrated. Likewise, the bore 12 similarly provides a socket portion into which the upper 15 end of a suitable applicator 14 is positioned, and is thereby resiliently gripped so as to secure the applicator to connector 8 and thereby to the cap 1. In the embodiment illustrated, the applicator is of the quill and brush type, and it will be understood that any well known form of applicator 20 may be used, such for example as a glass rod. The wall 13 separating the bores 11 and 12 prevents any seepage of the liquid (such as might flow toward the upper end of the applicator 14 25 when in inverted position) into the bore 11, and hence assures that even should the liquid seep past the tightly fitting inner wall of the lower socket portion and the applicator rod, nevertheless the tight resilient gripping action exerted 30 by the upper socket portion on the peg 7 will be maintained.

It is also to be noted that by making the member 8 of a diameter substantially less than the inner diameter of the neck of the bottle 1 eliminate 35 any sticking of the connector to the neck, such as is inevitably usually existing in such devices from liquid adhering to the usual form of stopper which fits the neck fairly snugly. Any adhesion which might be present from such liquid as comes into contact with the limited area 40 of the flange 9 as is in contact with the upper lip of the bottle is not sufficient to cause the connector to be withdrawn from the peg 7. In this connection it is pointed out that the gripping 45 action exerted between the peg 7 and the socket into which it is positioned is similar to that of a rubber tube tightly fitting over a plug or rod, and the stretched condition of the tubular walls surrounding the peg 7 is such as to furnish an 50 extremely strong connecting means. This gripping action is somewhat further enhanced at the portion adjacent the top wall 2 by means of the engagement between the outer peripheral edge of the flange 9 and the inner adjacent surface of 55 the skirt 3. Similarly, when in use the gripping action of the lower socket portion on the upper end of the applicator 14 is such that any force 60 exerted against the lower end of the applicator tending to pull the same out of its engaging socket merely tends to stretch the socket portions axially and thereby increase the gripping action both on the peg 7 and the end of the applicator 14.

Having thus described my invention with particularity with reference to its preferred form, it will be obvious to those skilled in the art, after understanding my invention, that other changes and modifications may be made therein without departing from the spirit and scope of my invention, and I aim in the appended claims to cover such changes and modifications as are within the scope of the invention.

What I claim is:

1. In a combined container closure and applicator, the combination of a cap having a top wall

provided with a depending skirt portion for engaging said container and a peg extending downwardly from said top wall and positioned within said skirt, a connecting member positioned within said skirt and provided at its upper end with a first socket portion providing means for securing said connecting member to said peg and at its lower end with a second socket portion, an applicator having its upper end extending into said second socket portion and supported in position thereby. 5

2. In a combined container closure and applicator, the combination of a cap having a top wall provided with a depending skirt portion for engaging said container and a peg extending downwardly from said top wall and positioned within said skirt, an elastic connecting member positioned within said skirt and provided at its upper end with a first socket portion in resilient frictional engagement with said peg and at its lower end with a second socket portion, the bores of said socket portions being discontinuous axially of said connecting member and being separated by an imperforate wall portion, an applicator resiliently frictionally held in said second socket portion. 10

3. In a combined container closure and applicator, the combination of a cap having a top wall provided with a depending skirt portion for exteriorly engaging the neck of said container and a peg extending downwardly from said top wall and positioned within said skirt, an elastic member within said skirt, said member having an upper outwardly extending flange and an integrally depending central stud portion of a lesser diameter than the internal diameter of the neck of said container and bores extending axially inwardly from respective ends of said member with an imperforate wall separating the adjacent inner ends of said bores, said member being seated with its flange against the inner face of the top wall of said cap and being held in position by the resilient frictional engagement of said peg positioned within said top bore, and an applicator held in position by the resilient frictional engagement of its upper end within said lower bore of said member. 30

4. In a combined container closure and applicator, the combination of a cap having a top wall provided with a depending skirt portion for exteriorly engaging the neck of said container and a peg extending downwardly from said top wall and positioned within said skirt, an elastic member within said skirt, said member having an upper outwardly extending flange adapted to overlie the mouth of said container and an integrally depending central stud portion of a lesser diameter than the internal diameter of the neck of said container and bores extending axially inwardly from respective ends of said member with an imperforate wall separating the adjacent inner ends of said bores, said member being seated with the upper face of its flange against the inner face of the top wall of said cap and the peripheral edge of said flange in contact with the inside wall of said skirt and said peg being positioned within said top bore, whereby said member is held in position within said cap by resilient frictional engagement, and an applicator held in position by the resilient frictional engagement of its upper end within said lower bore of said member. 50
